corporation of Ohio

Application September 17, 1936, Serial No. 101,199

6 Claims. (Cl. 135—20)

This invention relates to umbrellas.

One of the principal objects of the invention is the provision of an umbrella having a rib structure so arranged that a reverse curvature is imparted to the cover to provide a pleasing contour, and which is of such character that this desirable result obtains in a structure having the simplicity and reliability of a conventional umbrella.

10 Another object of the invention is the provision of an umbrella of the character mentioned comprising a central staff having a main rib structure extending from adjacent the staff end, and an auxiliary rib structure that is attached 15 to and extends above the main rib structure independently of any direct connection to the staff.

Another object of the invention is the provision of an umbrella having a rib structure that is arranged to impart a reversed curvature to the 20 umbrella cover and is constructed so that an advantageous reduction in length obtains by lowering the umbrella to the collapsed position.

Other objects and advantages of the invention will be apparent from the following description, 25 the accompanying drawings, and the appended claims.

In the drawings, which disclose a preferred embodiment of the invention,

Fig. 1 is a side elevational view of an umbrella constructed in accordance with this invention;

Fig. 2 is a fragmentary side elevational view showing the umbrella rib structure in extended position;

Fig. 3 is a fragmentary plan view of the rib structure of the umbrella; and

Fig. 4 is a fragmentary vertical sectional view as indicated by the line 4—4 on Fig. 1.

In the drawings, in which like characters of reference designate like parts throughout the several views thereof, there is illustrated an umbrella of the general type known to the trade as a garden umbrella. Umbrellas of this general character are frequently made to an extremely large size, sometimes having a diameter in excess of eight feet. To be a commercially acceptable article they are required to possess the usual features of utility common to conventional umbrellas, and in addition they usually incorporate features of ornamentation and the like in order to produce an effect more pleasing than is found in umbrellas that serve merely as a protection against the elements. Garden umbrellas and the like are generally arranged so that they may be collapsed when desired in order that they 55 may be rendered portable. They are frequently

constructed with a central staff or stick of several sections which may be taken apart in order that the umbrella in collapsed condition may be more readily handled. Such umbrellas, even when provided with detachable staffs, are of such size that additional means for reducing the overall collapsed length are of advantage.

In the umbrella here under consideration a pleasingly curved contour is obtained in a structure providing reliability of construction, a desired degree of weather-tightness, and additionally the arrangement is such that closing movement of the umbrella results in a shortening of the umbrella lengthwise of the staff.

Referring now more particularly to the drawings, the umbrella comprises a central staff 10 which, at its lower end, has provision for the application of an extension staff such that the umbrella may be raised to any desired elevation. As shown, the lower end of the staff 10 terminates in a sleeve portion 11 which functions as a socket for reception of an extending staff portion 12. The upper end of the staff 10 has affixed thereto means for attachment of a plurality of main ribs 14. As shown, the ribs are attached for pivotal movement with respect to the staff through provision of a collar 15 having a sleeve-like part 16 that is receivable upon the staff end of reduced diameter as indicated at 17. The collar is fixed to the staff end as by the provision of one or more nails of which one is indicated at 18. The collar has formed thereon an annular flange 20 having a peripheral groove 21. The flange is also provided with angularly spaced slots 22 which receive the inner ends of the main ribs 14 that are held in assembled relationship therewith through provision of a wire ring 23 that lies within the slot 21 and functions as a pivot upon which the ribs may move.

Extension or collapse of the umbrella is accomplished through provision of a runner 25 that is slidable upon the staff 10 and which has extending therefrom brace rods 26 that connect to the main ribs 14 by pivotal attachment as indicated at 27. A latching device, such as is indicated at 28 on the staff 10, serves to engage the runner 25 to hold the rib structure in extended position. In considering an umbrella structure of this general character from the viewpoint of compactness and portability it is to be noted that even in umbrellas incorporating a telescopically separable staff there is a minimum staff length which is limited by the traverse of the runner 25. In other words, that portion of the staff extending from the point of attachment of the ribs may not 55

be shorter than the distance from that point of attachment to the position of the runner in the closed position of the umbrella.

The main ribs 14, which are shown to be of equal angular spacing, are normally straight except for perhaps a short curved portion at the extreme outer ends. In the collapsed position of the umbrella they will lie substantially parallel to and closely adjacent the staff. They are constructed of a material sufficiently resilient that when extending the umbrella they may be deformed to conform to the shape of the cover.

The reversed curvature of the cover, referred to above and which is defined in the trade as a "pagoda type" umbrella, is accomplished through provision of an auxiliary rib structure which is attached to the main rib structure and projects thereabove in a direction opposite to that of the staff 10. As shown, auxiliary ribs 30 are provided having pivotal connection at 31 with the main ribs intermediate the attachment of the main ribs to the collar 15 and the connection of the main ribs at 27 to the brace rods. In the illustrated embodiment of the invention the auxiliary ribs 30 are provided for alternate main ribs as it has been found that such an arrangement provides a structure of adequate strength for the purpose intended. The auxiliary ribs 30 are joined to a collar 33 which, for convenience in manufacturing and assembly, may be similar to the collar 15 that is attached to the staff 10. The collar 33 is entirely independent of any direct connection with the staff 10 and, during opening and closing of the umbrella, it moves with respect to the staff. The path of movement of the collar 33 is axial with respect to the staff 10 because of the symmetrical relationship of the parts to which it is attached and, because of the coordination of those parts as to length, the collar moves in the collapsed position of the umbrella to a position closely adjacent the end of the staff 10. As is shown in the drawings, the collar 33 moves in the extended position of the umbrella to a position that is removed from the shaft end a material distance.

The auxiliary rib collar 33 is arranged to permit attachment of the umbrella cover thereto in such a manner that it is rendered secure and weather-tight, and it also serves as a means of locating and holding the cover concentrically with respect to the main rib structure. As shown, a plug 35 is received within the sleeve 36 of the collar 33 and has a shouldered lower end 36 which is quite narrow and which extends but a short distance below the collar. The opposite end of the plug extends beyond the collar sleeve as indicated at 37 and thus affords a projection for engagement of the cover and for attachment of suitable means by which this portion of the cover structure is rendered weather-tight. As shown, the cover 40 is constructed with a central aperture of such size to be receivable on the plug end 37; suitable reinforcing being provided at the aperture rim to provide a structure that will effectively resist tearing in the normal course of use. An overlying cap 42 is provided which telescopically engages the plug end 37 and overlies the central section of the cover. In the illustrated embodiment of the invention a decorative fringe 43 is incorporated in the assembly and is placed over the cover and beneath the cap 42; the related sizes of these various parts being such that the cap may be forcibly applied so that all of the parts are securely held. By constructing the plug 35 of wood

the collar and cap may be nailed thereto so that a permanent relationship is obtained. As shown, a nail 44 holds the collar in place while a nail 45 passes through the cap into the plug.

As mentioned above, the proportioning of the several parts constituting the auxiliary structure is such that the plug and collar of this structure stand in a position remote with respect to the staff end when the umbrella is in the open position, and move to a position closely adjacent the staff end when the umbrella is collapsed. As shown, the relationship of parts is such that in the open or extended position of the umbrella the auxiliary ribs 30 stand upwardly from the main ribs at an angle of the order of 45° which carries the auxiliary rib plug and collar a material distance from the end of the staff 10. When collapsed the auxiliary ribs 30 lie parallel to the main ribs 14.

In preparing the cover fabric for the umbrella the material is so cut and joined to provide the desired contour including the reverse curvature of surface that provides the pagoda effect. By properly shaping the material of the cover it may be caused to follow generally the direction of the auxiliary rib structure and to curve gradually into that surface portion outwardly of the central upstanding part which follows the contour of the main ribs 14. As the radial length of the cover closely approximates the effective length of the rib structure, which is the length of the auxiliary ribs plus the length of the main ribs from the point of attachment of the auxiliary ribs to the outer end of the main ribs, the cover is maintained taut in the extended position and is likewise sufficiently stretched in the collapsed position to permit of easy handling of the umbrella. The desired smooth surface of the cover also obtains through the proper positioning of attaching means shown in the form of clips 50 which are clamped to the cover and slidably engage the rib structure. The positioning of these clips is such that the innermost clips are attached to the ribs a distance outwardly of the attachment of the auxiliary ribs to the main ribs which is a positioning corresponding to the termination of the more abrupt curve of the central portion of the cover. In other words, the central portion of the cover is given some freedom of movement. As the portion of the cover inwardly of the innermost clips incorporates the reversed curvature, and as there are no clips within this area, the cover may assume a contour that is circumferentially uniform and without objectionable depressions as might be caused by the presence of clips within this area.

It is believed that it is now clearly apparent that the practice of this invention results in an umbrella of pleasing appearance, of simple and sturdy construction, and one in which an advantageous reduction in length takes place upon movement to a collapsed position. Further, these results are accomplished in an umbrella structure in which a multiplicity of sliding connections are avoided, and in which those parts constituting the center of the umbrella have a relationship such that a weather-tight assembly is readily obtained.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. An umbrella comprising a central staff, cover supporting ribs having their ends directly connected adjacent an end of said staff and movable thereon from a collapsed to an extended position for support of a cover, and an auxiliary cover supporting means for supporting the cover adjacent the center of the umbrella at an elevated position with respect to said ribs, said auxiliary means being attached to the ribs outwardly of the points of attachment of the ribs to the central staff and extending over and spaced from the staff end.

2. An umbrella comprising a central staff, cover supporting main ribs connected adjacent an end of said staff and movable thereon from a collapsed to an extended position for support of a cover, auxiliary cover supporting means for supporting the cover adjacent the center of the umbrella at an elevated position with respect to said main ribs comprising an auxiliary rib assembly spaced from and extending over the staff end and having attachment to the umbrella only by connections to the main ribs.

3. An umbrella of the character described comprising a central staff, main cover supporting ribs pivotally connected adjacent the upper end of said staff and angularly movable from a collapsed to an extended position, and means for supporting the cover center at an elevated position with respect to said ribs comprising a central supporting member spaced from and extending over the staff end and short ribs connected to the main ribs at a distance from the staff end and constituting the sole support for said supporting member.

4. An umbrella comprising a central staff, a plurality of cover supporting main ribs connected at their ends to said staff adjacent an end thereof, means for moving the ribs from a collapsed to an extended position, auxiliary ribs connected to the main ribs and extending towards one another from their points of attachment to the main ribs, and a fitting independent

of the staff joining said auxiliary ribs at a point in axial extension of the staff and movable with the rib structure from a remote spacing with respect to the staff end in extended position of the umbrella to a position closely adjacent the staff 5 end in the collapsed position of the umbrella.

5. An umbrella comprising a central staff, a plurality of resilient main ribs pivotally connected to said staff adjacent an end thereof and extending outwardly therefrom in angular spaced relationship, a runner on the shaft, brace rods extending from the runner and connecting to the main ribs inwardly of their ends, auxiliary ribs attached to the main ribs inwardly of the points of attachment of the brace rods to the main 15 ribs, said auxiliary ribs extending centrally towards one another, and a fitting pivotally connecting the auxiliary ribs in assembly and spaced outwardly of the staff end by an amount such that in the extended position of the main ribs 20 the auxiliary ribs stand outwardly therefrom at an angle of the order of 45° and in collapsed position of the main ribs the auxiliary ribs lie substantially parallel to the main ribs with the fitting closely adjacent the staff end. 25

6. An umbrella comprising a central staff, a plurality of main ribs connected to said staff adjacent the upper end thereof, means for moving the ribs from a collapsed to an extended position, auxiliary ribs pivoted to the main ribs and extending above the staff, a fitting independent of the staff joining said auxiliary ribs at a point in axial extension of the shaft, a cover on said main ribs and on said fitting, said fitting including a cap portion providing a fixed attachment of the 30 cover to the fitting, said fitting being movable with the rib structure from a remote spacing with respect to the staff end in the extended position of the ribs to a position closely adjacent the staff end in collapsed position of the ribs, the coordinated movement of the ribs and the fitting being such that the cover is held substantially taut in either position of the ribs. 40
